Primary Examiner—Raphael Barkai*Attorney, Agent, or Firm*—Kolisch, Hartwell, Dickinson, McCormack & Heuser[57] **CLAIM**

The ornamental design for children's ride-on vehicle, as shown and described.

DESCRIPTION

FIG. 1 is a top plan view of a children's ride-on toy vehicle showing my new design, with visible environmental structure shown in broken lines;

FIG. 2 is a left side elevational view thereof, with the right side elevational view thereof being a mirror image of FIG. 2, and with visible environmental structure shown in broken lines;

FIG. 3 is a front elevational view thereof, with visible environmental structure shown in broken lines;

FIG. 4 is a rear elevational view thereof, with visible environmental structure shown in broken lines;

FIG. 5 is a top plan view of an alternative embodiment of my new design, with visible environmental structure shown in broken lines;

FIG. 6 is a left side elevational view thereof, with the right side elevational view thereof being a mirror image of FIG. 5, and with visible environmental structure shown in broken lines;

FIG. 7 is a front elevational view thereof, with visible environmental structure shown in broken lines; and,

FIG. 8 is a rear elevational view thereof, with visible environmental structure shown in broken lines.
